UNITED STATES PATENT OFFICE.

EDWARD A. CONNER, OF BRIDGEPORT, CONNECTICUT, ASSIGNOR TO AMERICAN CHAIN COMPANY, INC., A CORPORATION OF NEW YORK.

CABLE-MAKING MACHINE.

Application filed July 10, 1922. Serial No. 574,103.

To all whom it may concern:

Be it known that I, EDWARD A. CONNER, a citizen of the United States of America, residing at Bridgeport, in the county of 5 Fairfield, State of Connecticut, have invented certain new and useful Improvements in Cable-Making Machines, of which the following, taken in connection with the accompanying drawing, is a specification.

10 One object of the invention is the construction of a cable-forming machine which will involve in its operation the forming of the strands into helices before laying them in position to constitute a component part 15 of the cable.

Another object is the construction of a cable-forming machine that will operate in the manner above described and that will form the strands into helices without twisting, viz, by a continuous bending operation not involving the subjection of the wire to angular distortion with respect to its axis.

By way of explanation in connection with the foregoing statement, attention is called to the fact that in the manufacture of the usual wire rope composed of a core and surrounding strands the outer or surrounding strands are bent upon a line, which, previous to the bending, constituted a helix on the surface 30 of the wire. This process obviously involves a twisting of the wire. In the method carried out by my machine the line of contact of each outer strand with the core is a straight line parallel with the axis of the wire, considering the wire in its condition 35 prior to the pre-forming and laying. In the conventional method first above described the result is an outer strand in which each fibre has been alternately subjected to tension and compression. In the process carried out by my machine, on the contrary, some fibres are subjected to compression and some to tension, but there is no transition from compression to tension in 40 the same fibre.

I am aware that previous attempts have been made to form cables by processes which purport to attain the same result as the process carried out by my machine, but 45 in these attempts the helices were formed during the process of laying the strand, that is, they were the result of bending the strands against and about the core. Cable so made, however, failed to lie flat or

straight when released, which made it not 55 only unsuitable for many purposes but also inconvenient to handle.

Another object of the invention is the construction of a cable-making machine capable of functioning in the manner above described if desired and which is also characterized by adaptability for operation at relatively high speeds, this result being accomplished by a highly efficient means of balancing the rotating parts and confining the 60 radii of gyration of those parts to relatively 65 small values.

Another object is the construction of a cable-making machine of the character 70 above described in which the wire-supply carrying members rotate on a common axis.

Another object is the construction of a cable-making machine in which provision is made for winding a reserve spool of supply wire contemporaneously with the drawing 75 off of wire to form the cable.

Another object is the construction of a cable-making machine provided with demountable wire-supply spools.

Another object is the construction of a 80 cable-making machine of such character that the wire-supply spools all rotate on the same axis.

Another object is the construction of a 85 cable-making machine in which all the wire-supply spools rotate on the same axis and in which, furthermore, provision is made for easily and quickly removing the wire-supply spools and interchanging them.

Another object is the construction of a 90 cable-making machine of such character that all the wire-supply spools rotate on the same axis and in which, furthermore, provision is made for removing the wire-supply spools without the necessity of dismounting 95 any other parts of the machine.

Another object is the construction of a cable-making machine which will make cable that will lie "dead" when not under tension.

Another object is the construction of a 100 cable-making machine which will make cable characterized by the fact that any given fibre of each strand is subjected to the same kind of stress throughout, that is, compression or tensile stress, as the case 105 may be.

Another object is the construction of a machine that will make cable characterized

by the fact that the outer strands hug the core closely by virtue of a "set" produced in forming them.

Referring to the drawings:

5 Figure 1 is a plan view of the machine, showing, however, only two of the stranding units, the remaining stranding units being omitted for the reason that they are in all respects similar to those shown.

10 Figure 2 is a view, in side elevation, of the machine.

Figure 3 is a detailed view of one of the stranding units, showing certain parts broken away for the sake of clearness.

15 Figure 4 is a vertical section on the line 4—4 of Figure 1.

Figure 5 is a detached view, showing the hollow spindle of the stranding unit, the performing nozzle and supply-wire guide

20 pulley.

Figure 6 is an end view of one of the wire-supply spools.

Figure 7 is a side view of one of the wire-supply spools showing the complementary halves of the same disengaged from one another.

25 The machine as shown and described herein consists of a series of what I term "stranding units," the number of stranding units varying with the number of strands of which the cable is to be composed and, in addition, mechanism for drawing the core as the strands are formed and laid and for drawing off the cable as it is completed. As

30 the stranding units are all similar and may vary in number as desired, only two are shown in the drawings and a description of one of these which I indicate in Figures 1 and 2 by the letter "A" will suffice for all.

40 The machine shown in the drawing is adapted for making cable composed of a core strand surrounded by a suitable number of outer strands. It is to be understood, however, that the incorporation in the cable 45 of a core strand is not essential to the operation of the machine nor to the structure of the completed cable. The presence of a core strand is, however, usually desired, especially in a cable which consists of more than 50 three or at the most four outer strands, and therefore I have illustrated a machine adapted for making a cable with a core.

55 The machine includes for convenience in mounting the rotating parts a table 1 supported by suitable standards 2. On the table 1 are erected a series of stranding units of which that indicated by the letter "A" in Figures 1 and 2 and shown in detail in Figure 3 will serve as an example, the 60 others, as hereinabove stated, being in all respects similar to it. Each of these several units includes a hollow spindle 3, and the units are arranged in tandem, that is, in such relative positions that the axes of the 65 several spindles are coincident with each

other and therefore the core wire 4 together with the outer strands as they are successively laid may be drawn continuously through the spindles. The core wire mechanism may consist of the core-wire supply reel 5 suitably mounted by any convenient means and the drawing-off mechanism indicated by the letter "B" in Figures 1 and 2. The principal function of the drawing-off mechanism is to maintain the core and cable under suitable tension and to move it at a speed coordinated with the speeds of the several stranding units. A suitable drawing-off mechanism may consist of the pulleys 6 and 7, the pulley 6 being a drive pulley mounted on a shaft 8, which, in turn, carries beveled pinion 9. The beveled pinion 9 meshes with the beveled pinion 10 mounted on the shaft 11, which, in turn, carries the gear 12. The gear 12 meshes with the pinion 13 mounted on the lay shaft 23, and, as will be obvious, rotation of the lay shaft causes the pulley 6 to be rotated. On the shaft 8 is also mounted a sprocket 14, and on the shaft 15, which carries pulley 7, is mounted another sprocket 16. The sprockets are connected by an endless sprocket chain 17 in the usual manner and consequently as the pulley 6 rotates, the pulley 7 rotates at the same speed. The tension on the completed cable is created by passing it a sufficient number of times about the pulleys 6 and 7, whereby suitable friction is caused. As the cable passes off the pulley 6, it may be reeled or disposed of in any desired manner.

10 The moving parts of each stranding unit are mounted on a pair of standards 18 and 19 which support bearings 20 and 21. The bearing 21 supports journal 22 of the outer member 24 of a suitable draw clutch, the journal being hollow and rotatable in the bearing 21. The fact that the journal is hollow makes it adaptable also as one bearing for the spindle 3, the other bearing for the spindle 3 being the bearing 20. On each of the hollow spindles are mounted two spools for containing a supply of wire, one of which, namely, that indicated by the letter "C," may be termed the wire-supply spool, and that indicated by the letter "D" the reserve wire-supply spool. These spools are, however, constructed in all substantial respects alike and are interchangeable for the purposes hereinafter more particularly described.

11 A detailed view of one of these spools is shown in Figures 6 and 7, from which it appears that it is composed of complementary parts, 25 and 26, which are adapted to be assembled on the spindle and secured together by engaging lugs 27 on the part 26 with the lugs 28 on the part 25. Clearance indicated by the numeral 29 is provided to allow for the interlocking of the lugs, and a 12 slideable collar 30 is mounted on the shaft and

is capable of being clamped in any desired position by means of a set-screw 31. This collar serves to keep the wire-supply spools in position on the spindle. It is obvious that when the spool "C" is free from wire it may be demounted by loosening the set-screw 31, moving the collar 30 along the shaft, then slipping the part 25 a sufficient distance along the spindle to disengage the lugs, whereupon the spool may be removed from the spindle in separate halves. Thereupon the other spool "D", which may be assumed to be filled with wire, may be moved up along the spindle to take the place of the spool "C". The spool "C" may be then reassembled in place of the spool "D", whereupon it is in position to receive wire in the manner hereinafter described.

Fixedly mounted on the spindle 3 is a flyer, composed of arms 32 and 33, the arm 32 carrying the grooved rolls 34, 35 and 36, which serve to guide the wire from the wire-supply spool "C" in the proper manner and direction to be guided into the die or pre-forming nozzle which is hereinafter further referred to. The mounting of the arms of the flyer may be accomplished by rigidly attaching them to the hub 37 which is a part of the bearing 38. The hub is fixedly mounted on the spindle by any convenient means such as the key 39. The bearing 38 also carries eccentrically mounted within it the helical die or pre-forming nozzle 39¹, which may consist of a rod of suitable material provided with a helical groove 40. The other arm 33 of the flyer carries a brake shoe 41 adapted to exert slight pressure on the arm of the particular spool of the pair which is delivering wire for the forming of the cable, that is, for example, in Figure 1 the spool "C". The motion of the spool "C" is therefore a resultant of two motions, one of which is the rotation of the spindle and the other is the rotation of the spool "C" on the spindle latter motion being determined by the rate at which wire is drawn through the pre-forming nozzle to be laid on the cable.

On the other hand, the reserve wire-supply spool "D" is normally fixedly mounted on the spindle, this mounting, however, being through the medium of the clutch hereinbefore mentioned, which is preferably adapted to be automatically released at a predetermined time. The clutch, as stated above, may consist of the outer member 24, which may be part of the bearing 22, the inner member 42 and the slide member 43 carrying the tapered rolls 44. The clutch may be provided with a control lever 45 and collar 46, the control lever 45 being pivoted at 47 and carrying the roll 48. Lever 49 is pivoted at 50 and is provided with a cam 51. The lever 45 is spring-pressed by the spring 50 to hold the clutch in release, but

as the lever 49 is also spring-pressed by the spring 53 to maintain the cam 51 against the rolls 48, the release of the clutch does not take place until the lever 49 is forced backwardly against the tension of spring 53, 70 which occurs only when the diameter of the coil 54 of wire has reached a pre-determined maximum.

The lay shaft, which has driving connection with all of the stranding units as well as with the tensioning device, is indicated by the numeral 23. It carries gears 55, which, in turn, mesh with gears 56 mounted on shaft 57, which also carries the gear 58, so that the gears 57 and 58 rotate together. The gear 58 meshes with the gear 59, which is rigidly connected to the bearing 22, and the gear 56 meshes with the gear 60, which is rigidly mounted on the spindle 3. The result of this construction is that as the lay shaft rotates it operates to rotate the spindle and, consequently, the flyer. At the same time, assuming that the spool "D" has not received a full load of wire, the spool "D" is rotated independently of the motion of the spindle, thus drawing wire from the reel 61 or from any other suitable source of supply. As soon as the diameter of the coil of wire of spool "D" has reached a predetermined dimension, which is fixed by the needs of the particular case in hand, the clutch is released and the wire is cut. The spool "D" is then ready to replace the spool "C" as soon as the supply of wire on the latter has become exhausted. In order to make rigid connection between the inner member of the clutch and the spools, the inner member of the clutch is squared at the end as shown at 62, the squared end being adapted to fit a square mortise 63 in the spool. To facilitate independent motion of the spools "C" and "D" the bushing 49¹ may be interposed between them.

The die or pre-forming nozzle 39¹ may, as above stated, consist of a rod provided with a helical groove of proper depth to accommodate the particular wire in use and of suitable pitch to properly pre-form the wire for the particular cable in process of manufacture. Obviously, the distance from the bottom of the groove 40 to the axis of the die determines the diameter of the helix formed and it is preferable that the diameter of this helix be slightly less than the diameter of the core wire, in order to insure that the former shall hug the latter closely.

It is to be understood that the speeds of the various parts are coordinated with each other as accurately as possible; viz: the ratios of the gears which drive the flyer and the reserve wire-supply spool are such that the wire-supply spool is certain to be filled in ample time in advance of the exhausting of the wire on the wire-supply spool "C". The speed of the tension mechanism is 130

regulated by employing driving gears of suitable ratio to draw the core through the several spindles at the proper speed to enable the outer strands to be laid closely and 5 regularly. Furthermore, as has already been stated, the pitch of the pre-forming nozzle is such that the helices thereby formed will be coordinated with the speed at which the cable is drawn through the 10 spindles. All of these quantities vary, as will be readily understood, with the character of cable that is in process of manufacture, the principal determining elements being the number of strands of which it is 15 composed and the pitch of the helices.

Assuming the inter-relation of parts as in the embodiment of the invention shown in the drawings, the preferred mode of operation is to rotate the shaft 3 and consequently 20 the reserve wire supply spool in a clockwise direction, the parts being considered as viewed from the position of the preforming nozzle and in the direction of the clutch mechanism, that is to say, from 25 right to left with reference to the drawings. The preforming nozzle consequently likewise revolves about the axis of the shaft 3 in a clockwise direction. As wire is drawn from the wire supply spool C, the latter rotates 30 in a counter-clockwise direction with respect to the shaft, although its direction of rotation with respect to any fixed radius is of course in clockwise direction. In other words, its motion is the resultant of the two 35 components, viz: the clockwise rotation of the shaft on which it is mounted and the counter-clockwise motion with respect to the shaft, the latter being of course the lesser of the two motions and the resultant 40 motion being consequently in a clockwise direction. The winding operation takes place by rotation of the reserve wire supply spool in a clockwise direction. The wire as it is drawn from the wire supply spool C 45 passes through the preforming nozzle which is adapted to form it into a right-hand helix and the thus preformed helix is laid accordingly to form a right-hand strand or cable. Of course, it is to be understood 50 that the foregoing description of the mode of operation of the machine is intended to apply only to the particular construction shown in the drawings. A left-hand strand or cable may, of course, be formed if desired by re-arrangement of parts such as is 55 well within the ability of the ordinary machinist.

In the foregoing description, I have referred 60 to the preforming member as a "nozzle". It is to be understood, however, that the particular type of preforming member shown is a preferred form only, and that any other suitable device may be utilized 65 for the purpose of bending the wire into suitable helical form.

Having thus described my invention, and with the knowledge that changes and modifications may be made that will nevertheless not depart from the spirit of the invention, I claim:

1. In the process of making stranded cable, the steps which comprise drawing the several strands through nozzles adapted to form them into helices and laying them, as they emerge from said nozzles, in position 75 to form component parts of the cable.

2. In the process of making stranded cable, the steps which comprise drawing the several strands through nozzles adapted to form them into helices and successively laying them in position as they emerge from 80 said nozzles to form component parts of the cable.

3. In the process of making stranded cables, the steps which comprise drawing 85 the several strands through nozzles adapted to form them into helices, laying them in position as they emerge from said nozzles to form component parts of the cable and at the same time rotating said nozzles about 90 the axis of the cable at a speed coordinated with the speed at which said strands are drawn through said nozzles.

4. In the process of making stranded cable, the steps which comprise drawing the 95 several strands through nozzles adapted to form them into helices and laying them in position as they emerge from said nozzles to form component parts of the cable and at the same time rotating said nozzles about 100 the axis of the cable substantially one revolution to each convolution of the helix.

5. In a machine for making stranded cable, a wire supply spool having its axis of rotation in the axis of the cable to be 105 formed, a helix-forming nozzle eccentrically mounted with respect to said axis, means for causing said nozzle to revolve about said axis, and means for drawing a strand from said wire supply spool and through 110 said nozzle to form a helix.

6. In a machine for making stranded cable, a wire supply spool having its axis of rotation in the axis of the cable to be formed and mounted to rotate idly, a helix-forming nozzle eccentrically mounted with respect to 115 said axis, means for causing said nozzle to revolve about said axis, and means for drawing a strand from said wire supply spool and thence through said nozzle to form a helix.

7. In a machine for making stranded cable, a flyer carrying wire guiding means and having its axis of rotation in the axis of the cable to be formed, a wire supply spool likewise having its axis of rotation in the axis of the cable to be formed and mounted to rotate idly, a helix-forming nozzle eccentrically mounted with respect to 125 said axis, means for causing said nozzle to revolve about said axis and for causing ro- 130

- tation of said flyer, and means for drawing a strand from said wire supply spool, thence through said wire guiding, and thence through said nozzle to form a helix.
- 5 8. In a machine for making stranded cable, a flyer carrying anti-friction wire guiding means and having its axis of rotation in the axis of the cable to be formed, a wire supply spool likewise having its axis of 70 rotation in the axis of the cable to be formed, a helix-forming nozzle eccentrically mounted with respect to said axis, means for causing said nozzle to revolve about said axis and for causing rotation of said flyer, and 75 means for drawing a strand from said wire supply spool and through said nozzle.
9. In a machine for making stranded cable, a flyer, anti-friction wire guiding means carried by said flyer, a wire supply 80 spool having its axis of rotation in the axis of the cable to be formed and mounted to rotate idly, a brake also carried by said flyer and adapted to bear on said wire supply spool to retard the free rotation thereof, a 85 helix-forming nozzle eccentrically mounted with respect to said axis, means for causing said nozzle to revolve about said axis and for causing rotation of said flyer, and means for drawing a strand from said wire supply 90 spool, thence through said wire guiding means, and thence through said nozzle to form a helix.
10. In a machine for making stranded cable, a series of stranding units arranged 95 in tandem, each stranding unit including a hollow spindle, said spindles being co-axial, a wire supply spool mounted to rotate idly on said spindle, a helix-forming nozzle mounted on said spindle eccentrically with 100 respect to the axis thereof, means for causing said spindle to rotate and consequently said nozzle to revolve about said axis, and means for drawing a strand from said wire supply spool and thence through said nozzle to form a helix.
11. In a machine for making stranded cable, a series of stranding units arranged 105 in tandem, each stranding unit including a hollow spindle, said spindles being co-axial, a wire supply spool mounted to rotate idly on said spindle, a helix-forming nozzle mounted on said spindle eccentrically with 110 respect to the axis thereof, means for causing said spindle to rotate and consequently said nozzle to revolve about said axis, means for drawing a strand from said wire supply spool and thence through said nozzle to form a helix, said means being adapted to prevent rotation of said helix.
12. In a machine for making stranded cable, a series of stranding units arranged in tandem, each of said stranding unit including a hollow spindle, a wire supply spool mounted to rotate idly on said spindle, a flyer 115 mounted on said spindle and carrying anti- friction wire guiding means and also speed retarding means to operate on said wire supply spool, a helix-forming nozzle eccentrically mounted on said spindle, means for drawing wire from said wire supply spool 120 through said guiding means and thence through said nozzle, means for causing rotation of said spindle and consequently revolution of the said nozzle about the axis of said spindle, and means for drawing a strand from said wire supply spool, thence through guiding means, and thence through said nozzle.
13. In a stranding unit forming a component part of a machine for making stranded cable, a rotatably mounted spindle, a wire supply spool carried by said spindle, said wire supply spool being composed of two complementary members, the plane of division of said members passing through 125 the axis of said spool, and means for locking said members together on said spindle and unlocking them.
14. In a stranding unit forming a component part of a machine for making stranded cable, a rotatably mounted spindle, a wire supply spool carried by said spindle, said wire supply spool being composed of two complementary members, the plane of division of said members passing through 130 the axis of said spool, and means for locking said members together on said spindle, said means consisting of interlocking lugs.
15. In a stranding unit forming a component part of a machine for making stranded cable, a rotatably mounted spindle, a wire supply spool slidably mounted on said spindle, said wire supply spool being composed of two complementary members, the plane of division of said members passing through 135 the axis of said spool, and means for locking said members together on said spindle.
16. In a stranding unit forming a component part of a machine for making stranded cable, a rotatably mounted hollow spindle, a wire supply spool slidably mounted on said spindle, said wire supply spool being composed of two complementary members, the plane of division of said members passing through the axis of said spool, means for locking said members together on said spindle, a reserve wire supply spool also slidably mounted on said spindle and capable of independent rotation 140 with respect thereto and also with respect to said first mentioned spool, and means for imparting rotary motion to said reserve wire supply spool.
17. In a stranding unit forming a component part of a machine for making stranded cable, a rotatably mounted hollow spindle, a wire supply spool slidably mounted on said spindle, said wire supply spool being composed of two complementary 145 members.

- 6 members, the plane of division of said members passing through the axis of said spool, means for locking said members together on said spindle, a reserve wire supply spool also rotatably mounted on said spindle and capable of independent rotation with respect thereto and also with respect to said first mentioned spool, means for imparting rotary motion to said reserve wire supply spool, said means consisting of a bushing on said spindle, clutch connection between said bushing and said reserve wire supply spool and means for imparting rotary motion to said bushing.
- 15 18. In a machine for making stranded cable, a lay shaft, a series of stranding units arranged in tandem, hollow spindles in said stranding units, the axes of said spindles being in alinement one with another, a rotatably mounted bushing constituting one bearing for said spindle, a plurality of wire supply spools slidably and rotatably mounted on said spindle, clutch connection between the said bushing and one of said spools, means for transmitting power from the said lay shaft to said bushing to impart rotary motion to the same and thence to said last mentioned spool, a flyer mounted on said spindle and carrying anti-friction wire guiding means and also a brake adapted to bear on the other of said spools, a helix forming nozzle also carried by said flyer, said nozzle being eccentrically mounted with respect to the axis of said shaft, and means operated by said lay shaft for drawing a strand from said last mentioned spool, thence through said wire guide and thence through said nozzle.
19. In a machine for making stranded cable, a lay shaft, a series of stranding units arranged in tandem, hollow spindles in said stranding units the axes of said spindles being in alinement one with another, a rotatably mounted bushing constituting one bearing for said spindle, a plurality of wire supply spools slidably and rotatably mounted on said spindle, clutch connection between the said bushing and one of said spools, means for transmitting power from the said lay shaft to said bushing to impart rotary motion to the same and thence to said last mentioned spool, a flyer mounted on said spindle and carrying anti-friction wire guiding means and also a brake adapted to bear on the other of said spools, a helix forming nozzle also carried by said flyer, said nozzle being eccentrically mounted with respect to the axis of said shaft, means operated by said lay shaft for drawing a strand from said last mentioned spool, thence through said wire guide and thence through said nozzle, the said wire supply spools being each composed of two complementary members, the plane of division of said members passing through the axis of said spindle, and means for detachably engaging the two complementary halves of said members.
20. In a machine for making stranded cable, a wire supply spool composed of complementary halves divided on a plane passing through the axis thereof, each of said halves being provided with lugs adapted to engage lugs on the other of said halves. 70
21. In a machine for making stranded cable, a wire supply spool composed of complementary halves separated on a plane passing through the axis of said spool, and means for detachably engaging said halves one with another. 75
22. In a machine for making stranded cable, a spindle, a plurality of wire supply spools mounted on said spindle each of said spools being composed of complementary halves, and means for detachably engaging said halves. 80
23. In a machine for making stranded cable, a spindle, a plurality of wire supply spools mounted on said spindle each of said spools being composed of complementary halves, means for detachably engaging said halves, means for drawing wire from one of said spools in the process of laying the same on a cable in process of manufacture, and means for supplying wire to the other of said spools as the same is rotated. 85
24. In a machine for making stranded cable, a stranding unit including a hollow spindle, means for continuously drawing a core wire through said hollow spindle, said spindle carrying means for supplying wire to be wrapped about said core as the same travels through said spindle. 90
25. In a machine for making stranded cable, a stranding unit consisting of a hollow spindle, a wire supply spool rotatably mounted on said spindle, means for drawing a core wire continuously through said hollow spindle, a preforming member eccentrically mounted on said spindle, and means for imparting rotary motion to said spindle. 95
26. In a machine for making stranded cable, a stranding unit consisting of a hollow spindle, a wire supply spool slidably and rotatably mounted on said spindle, a helix-forming nozzle eccentrically mounted on said spindle, means carried by said spindle for guiding wire from said spool to said nozzle, and means for drawing a core through said shaft and also wire from said spool through said nozzle. 100
27. In a machine for making stranded cable, a rotatably mounted hollow spindle, a plurality of wire supply spools demountably and rotatably carried by said spindle, said spools being interchangeable as to position, a flyer fixedly mounted on said spindle, said flyer being provided with anti-friction means for guiding wire, a brake carried by said flyer and adapted to exert yielding pressure 105
- 110
- 115
- 120
- 125
- 130

- on one of said spools, means for drawing wire from one of said spools and thence through said guiding means and thence through said nozzle and also for drawing a 5 core wire through said spindle, and means for imparting rotary motion to the other of said supply spools to wind wire on the same.
28. In a machine for making stranded cable, a rotatably mounted wire supply spool, a helix-forming nozzle mounted eccentrically with respect to the axis of said wire supply spool, means for drawing wire from said wire supply spool through said nozzle, and 10 means for causing said nozzle to revolve about said axis.
29. In a machine for making stranded cable, a loosely mounted wire supply spool, a helix-forming nozzle mounted to revolve 15 about the axis of said wire supply spool, wire guiding means between said spool and said nozzle, means for drawing wire from said spool through said guiding means and thence through said nozzle, and means for 20 causing revolution of said guiding means, and said nozzle about the axis of said spool.
30. In a machine for making stranded cable, a plurality of stranding units each consisting of a loosely mounted wire supply 25 spool, a hollow spindle, a helix-forming nozzle revolubly mounted eccentrically on said spindle, means for causing rotation of said spindle and means for drawing wire from 30 said wire supply spool through said nozzle, said means also drawing a core wire through 35 said spindle, the several units composing said stranding machine being arranged so that all of the spindles are co-axial.
31. In a machine for making stranded cable, a plurality of stranding units each consisting of a hollow spindle, the said spindles being co-axial and spaced from one another, a wire supply spool loosely mounted on each 40 of said spindles, a helix-forming nozzle eccentrically mounted near the end of each of 45 said spindles, means for causing rotation of said spindles, and means for drawing a core 50 wire through said hollow spindles and also for drawing wire from said wire supply spools through said helix-forming nozzles, and means for preventing said spools from 55 rotating on said spindles at a speed greater than as determined by the rate at which wire is drawn therefrom.
32. In a machine for making stranded cable, a plurality of stranding units, each of said stranding units comprising a hollow spindle, the said hollow spindles being co-axial and spaced from one another, a pair of 60 interchangeable wire supply spools mounted loosely and independently of each other on each of said spindles, a helix-forming nozzle eccentrically mounted on each of said spindles, means for causing rotation of said 65 spindles, and means for drawing a core wire
- continuously through said spindles, each of said wire supply spools consisting of two complementary parts and retained on the spindle by detachable means, and means for causing rotation of one of said wire supply 70 spools independently of the rotation of the other and independently of the rotation of said spindle.
33. In a machine for making stranded cable, a stranding unit comprising a spindle, a wire supply spool and a reserve wire supply spool both loosely mounted thereon, a bushing forming one of the bearings of said spindle and rotatably mounted, 75 said bushing having clutch connection with said reserve wire supply spool, and means for releasing said clutch when the diameter of a coil of wire wound thereon has attained a predetermined value.
34. In a machine for making stranded cable, a stranding unit comprising a spindle, a wire supply spool and a reserve wire supply spool both loosely mounted thereon, a bushing forming one of the bearings of 80 said spindle and rotatably mounted, said bushing having clutch connection with said reserve wire supply spool, and means for releasing said clutch when the diameter of a coil of wire on said reserve wire supply spool has attained a predetermined quantity, the said 85 spools being interchangeable and each being composed of two complementary halves detachably engaged to enclose said spindle.
35. In a machine for making stranded cable, a stranding unit comprising a rotatably mounted spindle, a wire supply spool and a reserve wire supply spool both loosely 90 mounted thereon and capable of rotation independently of each other, means for rotating said reserve wire supply spool independently of the rotation of said spindle and of said wire supply spool for a predetermined period, the said spools each being composed of two complementary parts detachably connected together to enclose said 95 spindle.
36. In a machine for making stranded cable, a stranding unit comprising a rotatably mounted spindle, a wire supply spool and a reserve wire supply spool both loosely 100 mounted thereon and capable of rotation independently of each other, means for rotating said reserve wire supply spool independently of the rotation of said spindle and of said wire supply spool for a predetermined period, the said spools each being composed of two complementary parts detachably connected together to enclose said 105 spindle, a helix forming nozzle eccentrically mounted with respect to said spindle, means for causing said nozzle to revolve about the axis of said shaft, and means for drawing wire from said wire supply spool through said nozzle.
37. In a machine for making stranded 110

cable, a stranding unit comprising a rotatably mounted hollow spindle, a wire supply spool and a reserve wire supply spool both loosely mounted thereon and capable of rotation independently of each other, means for rotating said reserve wire supply spool independently of the rotation of said shaft and of said wire supply spool for a predetermined period, the said spools each being composed of two complementary parts detachably connected together to enclose said spindle, a helix-forming nozzle eccentrically mounted with respect to said spindle, means for causing said nozzle to revolve about the axis of said shaft, means for drawing wire from said wire supply spool through said nozzle, and means for drawing a core wire through said shaft.

38. In a machine for making stranded cable, a plurality of helix-forming nozzles, sources of wire supply, means for forcing wire from said sources of wire supply through said nozzles, means for receiving the finished cable, and means for producing relative rotation as between said nozzles and said receiving means.

39. In a machine for making stranded cable, a plurality of helix-forming nozzles, sources of wire supply, means for forcing wire through said nozzles, means for receiving the finished cable, and means for producing relative rotation between said nozzles and said receiving means, the speed of said rotation being coordinated with the speed with which said wire is forced through said nozzles.

40. In a machine for making stranded cable, a plurality of helix-forming nozzles disposed substantially parallel with the cable line, sources of wire supply, means for propelling wire through said nozzles, means for receiving the finished cable and means for producing relative rotation as between said nozzles and said receiving means, the axis of said rotation being in the said cable line. 45

41. In a machine for making stranded cable, a plurality of helix-forming nozzles disposed substantially parallel with the cable line of the machine, sources of wire supply, means for propelling wire through said nozzles, means for receiving the finished cable and means for producing relative rotation between said nozzles and sources of wire supply on the one hand and said receiving means on the other. 50

42. In a machine for making stranded cable, a plurality of helix-forming nozzles disposed substantially parallel with the cable line of the machine, sources of wire supply, means for propelling wire through said nozzles, means for receiving the finished cable, means for producing relative rotation between said nozzles and sources of wire supply on the one hand and said receiving means on the other, the said speed of rotation being coordinated with the speed with which the wire is forced through the said nozzles to produce substantially one revolution of said receiving means to each convolution of the helically-formed wire. 65

EDWARD A. CONNER.
